UNITED STATES PATENT OFFICE.

FREDRICH C. HECKER, OF NEW YORK, N. Y., ASSIGNOR TO WILLIAM J. PETERSON AND FREDERICK C. HECKER, BOTH OF BROOKLYN, NEW YORK.

SAFE HAT-PIN.

1,203,330.

Specification of Letters Patent. Patented Oct. 31, 1916.

Application filed January 28, 1915. Serial No. 4,837.

To all whom it may concern:

Be it known that I, FREDRICH CHARLES HECKER, a citizen of the United States, and resident of the borough of Brooklyn, county 5 of Kings, city and State of New York, have invented certain new and useful Improvements in Safe Hat-Pins, of which the following is a specification.

In developing this invention it is my 10 intention to produce a device which will in appearance and general operation be very similar to the ordinary hat pin familiar not only to the user of such devices but to the general public at large. My object in so 15 doing is to avoid the necessity of instructing the user in the peculiarities of the operation of the device and to offer an article that will be devoid of all mechanical and manufacturing difficulties or objections.

20 In general appearance my device is not unlike an ordinary hat pin except for additional ornamentation which materially adds to its attractiveness and except for a slight increase in the diameter of the body of the 25 pin.

The following is what I consider the best means of carrying out this invention.

The accompanying drawings form a part of this specification, in which:—

30 Figure 1 is an elevation of the completed device. Fig. 2 is a sectional view of a portion thereof.

Similar reference numerals indicate like parts in all the figures where they appear.

35 At 1, I have indicated a pin and at 2 a head; these parts may be of ordinary construction and of ordinary size. The head may be of more or less ornate design and I may find it advisable to have the pin 40 proper of a slightly smaller diameter than usual. The pin body should be of steel and should be provided with a sharp point as indicated at 3.

Secured to the inner or under side of the 45 head 2, I arrange a tubular shield or thimble 4, and over the body of the pin I arrange an elongated tubular body 5; the tube 5 has an inside diameter sufficient to receive the pin 1 in free engagement as these parts are 50 to have a relative reciprocal movement longitudinally. The lower end of the tube 5, has its outer walls tapered upon an angle coincident with the angle of the pin point 3.

Secured to the tubular member 5 and ad- 55 jacent to the outer or upper end thereof I

arrange a shield 6 which may be formed of pressed or spun metal or of any other suitable material and which may be also shaped in, or provided with a decorative design. This shield 6 extends upward to a point 60 above the lower end of the tube or thimble 4 and although it closely engages the thimble 4 I do not intend that it shall be secured thereto.

Within the shield 6, and secured to the 65 tubular members 4 and 5 I arrange a compressible spring 7, which is adapted to urge the tubular members 4 and 5 away from each other in a longitudinal direction, and to prevent a complete disengagement of the 70 tubular members I may provide a slight enlargement 8 upon the short tube 4, and a similar enlargement 9 upon the longer tube 5. These enlargements may also be arranged to receive the pressure from the 75 opposite ends of the spring 7, and may further serve to retain the shield 6 in its proper operative position.

In operating this device the user receives 80 the shield 6 between the thumb and finger, and then with another finger depresses or forces inward the head 2 against the pressure of the spring 7. This movement ejects the point 3 of the pin body 1 outward through the inner or lower end of the longer 85 tubular member 5. In this position the pin is inserted into and through the hat and when it has been properly adjusted the hand is removed releasing the pressure upon the spring and allowing the spring to retrieve 90 the pin point into the tubular member 5, and now if the end of the member 5, which is adjacent to the point of the pin has been carefully finished it will be found that this member although it protrudes through a hat 95 cannot become injured or cannot injure a person or thing that comes in contact therewith. Upon removing the pin from the hat it is only necessary to pull the head 2, or shield 6. In the operation of removal the 100 action is exactly similar to an ordinary pin.

It will be understood that modifications 105 may be made within the scope of the appended claims without departing from the principle or sacrificing the advantages of this invention.

The length of the body member 1, and tube 5 may be increased or decreased at will, and the length, shape or diameter of any of the parts may be increased or decreased, so 110

likewise may the ornamentation be changed to satisfy special requirements. It is desirable however that certain of the general proportions be retained so that the point of the pin may be retrieved wholly within the tubular member 5.

Having carefully and fully described my invention what I claim and desire to secure by Letters Patent is:—

- 10 1. A hat pin having a plurality of tubular members in telescopic engagement, a spring for urging said members away from each other, and a shield over the adjacent ends of said tubular members and said spring and adapted to limit the movement of said tubular members as and for the purpose set forth.
- 15 2. A hat pin having a head and a body secured together, a short tubular member secured to said head, a longer tubular member telescoping into said first mentioned tubular member and in which the body of the pin is

free to reciprocate, the free end of said longer tubular member being tapered at an angle co-incidental to the point of said pin 25 a spring secured to each said tubular member and adapted to induce and limit the relative motion thereof, and a shield having each of its ends inturned and arranged over said spring and over the telescope joint of 30 said tubular member and an annular projection upon each said tubular member and within said shield, said projections being adapted to impinge upon the inturned ends of said shield to limit the opposite movement 35 of said tubular members all combined for joint operation as herein specified.

Signed at New York city, in the county of New York and State of New York this 2nd day of November, 1914.

FRED. C. HECKER.
